UNITED STATES PATENT OFFICE.

DALTON K. WILSON, OF WATERLOO, IOWA.

CULTIVATOR.

1,393,061.

Specification of Letters Patent. Patented Oct. 11, 1921.

Application filed December 13, 1919. Serial No. 344,612.

To all whom it may concern:

Be it known that I, DALTON K. WILSON, a citizen of the United States of America, and a resident of Waterloo, Blackhawk county, 5 Iowa, have invented certain new and useful Improvements in Cultivators, of which the following is a specification.

My invention relates to improvements in cultivators.

- 10 The objects of my improvements are, to supply for gardening or other purposes, a light, manually steered and controlled motor-propelled device, which has releasable locking-means for the steering mechanism 15 when the caster-wheels are released in a turning operation, and which has other releasable locking-means for keeping the caster-wheels longitudinal with the course traversed when the steering-mechanism is 20 released from the first-mentioned locking-means.

The invention herein embraces improvements in my United States Patent, No. 1,350,050, dated Aug. 17, 1920.

- 25 The above objects I have accomplished by the means which are hereinafter described and claimed, and which are illustrated in the accompanying drawings, in which Figure 1 is a side elevation of my improved cultivator, 30 parts thereof broken away; Fig. 2 is a plan view thereof with the prime motor removed, and parts broken away, and Fig. 3 is a front elevation thereof, with parts, including the prime motor, removed or broken away.

- 35 Similar numerals of reference denote corresponding parts throughout the several views.

My improved cultivator pertains particularly to walking-cultivators, but the 40 operating steering and tool controlling mechanisms thereof are entirely adaptable to riding-cultivators without any essential change in either mechanism.

A horizontally arranged rectangular 45 frame 1, supported on fixed hangers 5, is by this means mounted on the stub-axles 67 of a pair of carrying-wheels 84. Upon said frame is mounted a prime motor 73 upon whose power-shaft 72 is mounted a sprocket-pinion 71 in mesh with a sprocket-chain 70. This chain is in mesh with teeth of a sprocket-rim 69 which forms part of a differential gearing mounted upon a counter-shaft 64, whose ends are supported in bearings 63 upon fixed standards on said frame, 50 55

The differential gear is of the usual type with the like bevel-gears 61 and 62 on the respective shaft parts. A friction-clutch member 60 is combined with the housing of said gearing and it is moved into or out of operative engagement therewith by jointed arms 59 linked between it and lugs on the annularly grooved sleeve 58, the latter splined upon but longitudinally slidable on the section of the shaft 85 upon which it is 60 mounted. The bell-crank lever 55 is pivotally mounted at its angle upon a bracket 86 and one arm is formed into a fork 57 positioned within said annular groove, the other arm having a terminal pivotal connection 65 with a shifting-rod 53 movable through an opening in a standard 52 and provided with a rear terminal handle 54.

Upon the outer ends of the shaft sections 85 are fixed sprocket-pinions 64, which are 70 in mesh with sprocket-chains 65, the latter in mesh with like sprocket-rings 66 secured concentrically upon the inner faces of the spokes of the carrying-wheels 84 by means 75 of clamping-members 68.

Fixed hangers 6 below the cross-bar 75 of said frame depend thence downwardly, and their lower parts are bent horizontally outwardly, secured to and support the lower ends of the depending hangers 5, by means 80 of longitudinally positioned bars 7 carried from the hangers 6, secured to and rigidly connecting the hangers 6 and 5. The numeral 9 denotes a pair of longitudinally arranged horizontal gang-frames whose forward ends are pivoted for vertical rocking to the lower ends of swivel elements 8 which are mounted for horizontal rocking upon the said horizontally extending lower parts of the hangers 6. Soil-working tools 90 95 13 are mounted for vertical adjustment in bearing-blocks 12, the latter mounted for transverse adjustment on transverse horizontal tubular elements 11, the latter secured to and supported by mating clamp members 10 which are removably secured on the rear ends of the gang-frames 9.

The angle-bar frame elements 1 are connected rigidly by means of space cross-bars 2, 3 and 4, and a forward cross-bar 105 75. Under the cross-bar 2 is positioned a transversely arranged plate 19 whose middle portion is shaped with a segmental gear 20, the teeth thereof being directed rearwardly, and supported on a short ver- 110

tical shaft 74, mounted in a bearing-opening in said cross-bar.

The numeral 17 denotes a pair of longitudinal controller-beams whose forward ends are swiveled to the extremities of said plate 19 by universal-point elements 18. These beams extend rearwardly a considerable distance beyond the frame 1, and a short extension-bar 79 is pivotally connected to each on a pintle-bolt 78 with mating serrated members 77 and 78 whereby these bars, which have looped terminal handles 80, may be rocked vertically and secured in an adjusted position.

15 Upon the gang-frames 9 are erected fixedly tubular standards 14. Vertical plates 15, spaced from the outer faces of the upper ends of said standards are secured fixedly to the standards by pintle-bolts, and horizontal anti-friction rollers 16 are mounted rotatably on said pintles, spaced vertically. The interspace of each pair of rollers is traversed by one of the beams 17, so that the standards serve as supporting hangers 20 for the rear ends of the gang-frames 9.

A pair of caster-wheels 49 are positioned to the rear of the carrying-wheels 84, mounted on short axles 48 between spaced housing-bars 46. These bars are mounted by means 30 of bolts 47 to tubular standards 45 from which extend rearwardly fixed arms 44. The rear ends of the arms 44 are connected by means of pintle-bolts 43 to the opposite extremities of a transverse upwardly-bowed connecting-bar 42, upon whose medially bowed part is secured an angle-plate 40, whose upwardly-directed flange is medially rectangularly notched at 81.

Rock-shafts 88 are pivotally mounted 40 within the tubular standards 45 and extend downwardly from enlarged heads 89, the latter having sockets 90. In the sockets 90 are secured the ends of a medially bowed cross-bar 50. On the bowed part of said 45 cross-bar is secured a horizontal plate 51 having a pair of erect lugs connected by a pintle-bolt 34.

Referring now to Fig. 2, the numeral 22 denotes a medial longitudinal rock-bar 50 whose forward extremity is formed with a segmental rack 21 in mesh with the segmental gear 20. The bar 22 is pivoted on a pintle-bolt 23 extending through the frame cross-bar 3, and its rear part is bifurcated. 55 Its bifurcations 24 are fixedly secured to the forward ends of the tubular arms 25 which movably traverse the interspace of frame cross-bars 4 and 26 on both sides of the medial longitudinal line of the frame 60 and between and spaced from anti-friction rollers 29 rotatably mounted on pintle-bolts connecting said cross-bars. The rear extremities of the arms 25 are fixedly connected by means of a cross-plate 31 which carries a pair of depending lugs, and the latter

are pivotally mounted upon the said pivot-pintle 34 which connects the lugs on the plate 51.

Upon the plate 31 are a pair of transversely-spaced orificed erect lugs 32 connected by a pintle-bolt 33. The numeral 37 denotes a rock-arm having an integral terminal looped handle 39, and having a pair of longitudinally positioned slots which thus leave between them the narrow part 75 38 which is adapted to releasably fit into and engage the walls of the rectangular notch 81 in the erect flange of the angle-plate 40. The arm or member 37 has a pair of forwardly extending forks 36 which are pivoted upon the cross-pintle 33. Another pair of bifurcations 35 extend from said arm 37, and are orificed to receive the out-turned rear extremities of rods 91. The pivotal connections of the bifurcations 36 and 35 85 respectively, with the lugs 32 and said rods 91, are so relatively arranged that the arm 37 is, when in a lowered position with its engaging part 38 in engagement with the notch 81 held or interlocked with the notch, 90 by reason of being in or beyond a dead-center position.

The numeral 27 denotes a cross-body secured to and connecting the arms 25 in advance of the rollers 29 between the cross-bars 4 and 26. The ends of the cross-body 27 are shaped on the rear with like cam-faces or curved wedge-members 28 terminating outwardly with notched recesses or seats 30. The forward extremities of the 100 rods 91 are fixedly secured to the cross-body 27.

Operation: When the friction-clutch 60 is actuated by the handled rod 53, appropriately, the motor 73 propels the cultivator 105 ahead by the power transmission-means described.

As the cultivator shown is of the kind called a walking-cultivator, the person walking to the rear of it may steer it, turn it 110 right about, or manipulate the soil-working tools as follows:

When the handled rock-arm 37 is in the position shown, interlocked with the cross-bar 42, the latter is restrained from lateral movements, consequently, the caster-wheels 49 are kept in alinement with the course traversed. The bowing of the cross-bars 42 and 50 permits them to clear tall plants in a row between the carrying-wheels. The gang-frames with their implements may be controlled and moved by means of the beams 17 upon which the rear ends of said gang-frames are hung, but it should be noted that this is a slidable connection, so that in up and down movements of the beams, the implements may be raised or lowered or swung laterally without affecting the course of the cultivator as propelled ahead. The direction of movement of the cultivator is con- 125 130

- trolled, however, by the use of the same beams 17, when the latter are shifted longitudinally. In actuating the beams 17 in steering, they rock the gear 20 and rack 21 5 to turn the frame 1 with its carrying wheels 84 in the desired direction. In this change of direction, the other wheels 49 are utilized as fulcra. The beams may be swung laterally to shift the gang-frames laterally, without changing the direction of the cultivator. It will be seen that the steering and implement-shifting actions may be effected by different actuations of the beams 17 alone, and the operator hence has perfect control, 10 without need for using other or separated appliances to perform parts of the necessary acts. The beams 17 may be shifted longitudinally and simultaneously swung laterally, up or down, or with a compound of 15 these angular movements, to shift the gang-frames while also operating the steering elements.

When the handled arm 37 is lifted by swinging it upwardly, it is disengaged from 25 the cross-bar 42, so that the latter becomes a laterally movable connecting-rod between the wheels 49, permitting the whole cultivator to turn pivotally about the carrying-wheels 84. The frame 1 is thus made rigid 30 with the arms 25, caused by the locking of the cams 28 and notches 30 on the cross-body 27 with the rollers 29, as the rods 91 are drawn rearwardly when the arm 37 is 35 swung upwardly. Previously, the friction-clutch is thrown out of engagement to cause cessation of propulsion by the motor, and the beams 17 lifted and hung on hooks 82 on said frame. The handles 80 are shifted on their adjustable joints to permit beams to 40 be operated by persons of different heights.

One or more bolt-holes 92 may be provided in the landward end part of the cross-bar 42 to allow of the adjustably mounting therealong of the caster-wheel on that side, 45 when a plow-share is to be used, to permit appropriate tracking of said wheel.

Having described my invention, what I claim as new, and desire to secure by Letters Patent, is:

- 50 1. In combination, means of transportation, soil-working implements movably supported thereon, interconnected mechanisms for both steering said means of transportation and for variably shifting said soil-working implements and connected releasable means for locking said mechanisms in a certain relation to said means of transportation.

2. In combination, means of transportation, including carrying wheels, and caster-wheels, soil-working implements movably supported on said carrying-wheels, interconnected mechanisms for both steering said means of transportation and for shifting 65 said soil-working implements, and releas-

ably connected sets of locking-means for alternately holding said mechanisms in a certain relation to said carrying-wheels when the caster-wheels are released therefrom to swing laterally, and to prevent the caster-wheels from swinging laterally when said mechanisms are released. 70

3. In a combination, means of transportation, soil-working implements movably supported thereon, interconnected mechanisms 75 for both steering said means of transportation and for variably shifting said implements, and movably connected sets of engaging-means adapted respectively to be releasably alternately interlocked with said mechanisms and with said means for transportation, to permit variable control of the movements of the latter.

4. In combination, carrying-wheels, a frame mounted thereon, caster-wheels, gang-frames movably supported on said frame, and releasable locking-means movably connected between said frame, gang-frames and said caster-wheels to alternately lock the gang-frames on the caster-wheels relative to 80 said frame, or to releasably lock the caster-wheels against rocking. 85

5. In combination, carrying-wheels, a frame mounted thereon, caster-wheels, gang-frames movably supported on said frame, 95 means for shifting the positions of said gang-frames relative to said frame, and locking-mechanism supported movably on both said frame and said caster-wheels and movably connected to said gang-frames, and 100 adapted for actuation to alternately lock the gang-frames and their shifting-means to the frame, or to releasably lock said caster-wheels against lateral swinging movements. 105

6. In combination, carrying-wheels, a frame supported thereon, means for steering said carrying-wheels, gang-frames supported on said frame movably, and slidably linked to said steering-means for actuation therewith or independently thereof, caster-wheels connected to said frame, and locking-means for locking releasably said caster-wheels against lateral swinging. 110

7. In combination, carrying-wheels, caster-wheels, gang-frames movably supported by 115 said carrying-wheels, means for manually shifting said gang-frames, and operative locking-means supported on both said carrying-wheels and said caster-wheels and movable releasably relatively to alternately lock 120 the gang-frames to the carrying-wheels, and the caster-wheels against lateral swinging movements.

8. In combination, a frame, sets of carrying-wheels supporting said frame, implements movably supported on said carrying-wheels, means for changing the positions of certain of said carrying-wheels relative to the others thereof, means for shifting said implements, and sets of movable locking- 125 130

mechanisms, interconnected to each other and to said frame for alternately locking the gang-frames to the frame, and holding certain of said wheels in a desired relation 5 to the other wheels.

9. In combination, carrying-wheels, a frame supported thereon, caster-wheels, gang-frames movably connected to said frame, controller-bars movably connected to 10 said frame and each slidably connected to one of said gang-frames, mechanism connected between said controller-bars, said frame, and said caster-wheels operable by the controller-bars to change the direction of 15 movement of said carrying-wheels relative to said caster-wheels, said mechanism including alternative locking-devices for alternately releasably locking the mechanism to said frame while unlocking the caster- 20 wheels to permit them to rock laterally, and

the caster-wheels to track without such lateral swinging while releasing said mechanism to permit its use in steering the wheels.

10. In a device of the character described, carrying-wheels, a frame mounted thereon, 25 means for steering said device connected to said frame including longitudinally-movable members, gang-frames movably connected to said frame, standards rigidly fixed on said gang-frames, and loose connections 30 between said members and said standards, permitting free relative longitudinal movements to the members without shifting the gang-frames, or permitting such movements while permitting the members to simultaneously shift the gang-frames..

Signed at Waterloo, Iowa, this 26th day of November, 1919.

DALTON K. WILSON.
